 of Delaware

Application May 7, 1932, Serial No. 609,783
 In Great Britain May 15, 1931

4 Claims. (Cl. 250—33)

This invention relates to aerial systems and more particularly to systems in which aerials required for use for transmitting and for receiving purposes are mounted in such close relationship to one another that there is risk of interference by pick up upon leads associated with the receiving aerial of energy from leads associated with the transmitting aerial.

Though not limited to its application thereto, the present invention is well adapted for use on shipboard or at other stations erected on sites of limited area in cases in which short wave omnidirectional aerials or aerials (such, for example, as horizontal dipoles) associated with reflectors are suspended either horizontally or otherwise in fairly close relationship, such aerials being required for duplex operation. (It is, of course, quite common to associate dipole and other aerials with reflectors to minimize transmission in or reception from other than desired directions.) It will be appreciated that owing to restrictions of space the transmitting and receiving aerials will, in the great majority of cases, have to be erected in such relationship that there is serious risk of interference by pick up upon the down leads from the receiver aerial to the receiver, of energy radiated by the leads from the transmitter to the transmitting aerial.

The present invention has for its object to avoid this difficulty and utilizes the known fact that interference in wireless receiving apparatus may be prevented by shielding wires supported parallel to and close to an aerial lead wire or feed wire or other device to be protected.

According to this invention, a wireless signalling station comprises two aerials one for transmitting and one for receiving arranged fairly close to one another, feeding wires leading from a transmitter to the transmitting aerial, feeding wires leading from the receiving aerial to a receiver, and one or more grounded screening wires running parallel to and spaced from the leads to the transmitting aerial and/or the leads from the receiving aerial.

The grounded screening wire or wires may be grounded through an impedance or impedances, e. g. damping resistances.

Preferably, screening wires are associated both with the leads from the receiving aerial and the leads to the transmitting aerial.

In certain cases it may be desirable to employ a screening wire or wires associated with the receiver leads only in the manner described.

In some cases the distance between a screening wire and the associated down lead may be

conveniently one-quarter of the working wavelength.

The invention is illustrated in the accompanying drawing which shows schematically one way of carrying out the invention as applied to a shipboard installation.

Referring to the drawing, the installation there-in shown comprises two aerials AT, AR, one AT for transmitting and the other AR for receiving, these aerials being each constituted by a horizontal dipole and being suspended in the same straight line by suitable insulation and suspension means I and S between a pair of masts M, the inner and adjacent ends of the two aerials being, of course, insulated from one another by suitable suspension and insulation means I and S which are in the same straight line with the two aerials.

A pair of parallel down leads LT connect the transmitter T to the transmitting dipole as in the usual way and a similar pair of parallel down leads LR connect the receiving dipole to the receiver R. Parallel to and spaced from the down leads LT is a screening wire WT which is parallel to the said down leads and is carried at its upper end by suitable insulators I and suspension wires S from the general horizontal suspension. The lower end of the screening wire is earthed through a suitable resistance or impedance RT. A second screening wire WR and resistance RR is associated with the receiving aerial down leads in a similar manner.

The transmitter T and receiver R are situated as far apart as conveniently possible so that in the preferred arrangement the down leads from the transmitting aerial and from the receiving aerial diverge from one another as they come downwards, as shown, the screening wires being similarly divergent since they are parallel to the down leads with which they are associated.

The invention is particularly intended to neutralize the radiation from aerial feeder wires, which radiation is unavoidable in practice owing to the difficulty of matching the surge impedance of the feeder at its junction with the aerial.

I claim:

1. A wireless signaling system comprising a transmitting dipole and a receiving dipole arranged horizontally in the same straight line and insulated from one another, a pair of down leads from the transmitting dipole to an associated transmitter, a second pair of down leads from the receiving dipole to an associated receiver, a screening wire running parallel to and adjacent the down leads from the transmitting dipole, and

a further screening wire running parallel to and adjacent the down leads from the receiving dipole, said down leads and associated screening wires diverging from one another in a downwards direction.

2. A wireless signalling system comprising a transmitting dipole and a receiving dipole arranged horizontally in the same straight line and insulated from one another, a pair of down leads from the transmitting dipole to an associated transmitter, a second pair of down leads from the receiving dipole to an associated receiver, a screening wire running parallel to and adjacent the down leads from the transmitting dipole, and a further screening wire running parallel to and adjacent said down leads from the receiving dipole, said screening wires being intermediate said transmitting and receiving down leads.

3. A wireless signalling system comprising a transmitting dipole and a receiving dipole arranged horizontally in the same straight line and insulated from one another, a pair of down leads from the transmitting dipole to an associated transmitter, a second pair of down leads from

the receiving dipole to an associated receiver, a screening wire running parallel to and adjacent the down leads from the transmitting dipole, and a further screening wire running parallel to and adjacent said down leads from the receiving dipole, said screening wires being intermediate said transmitting and receiving down leads, said pair of down leads from the transmitting dipole and its associated screening wire diverging from said other pair of down leads and its screening wire in a downward direction.

4. A wireless signalling system comprising a transmitting dipole and a receiving dipole arranged horizontally in a straight line and insulated from one another, a pair of down leads from the transmitting dipole to an associated transmitter, a second pair of down leads from the receiving dipole to an associated receiver, screening wires having damping resistances therein running parallel to and adjacent the down leads from the transmitting and receiving dipoles, said screening wires being located intermediate said transmitting and receiving down leads.

NORMAN WELLS.
